CAMPER TRAILER

Bruce K. Ward, 1338 1st Ave. S.,
Minneapolis, Minn. 55403

Filed June 19, 1972, Ser. No. 264,142

Term of patent 14 years

Int. Cl. D12—10

U.S. Cl. D12—103

FIG. 1

FIG. 2

FIG. 3

FIG. 4

FIG. 1 is a perspective view of the camper showing my new design, the opposite side of the camper trailer being substantially a mirror image thereof.

FIG. 2 is a front elevational view thereof, to a larger scale.

FIG. 3 is a rear elevational view thereof, to a larger scale.

FIG. 4 is a top plan view thereof, to a larger scale.

I claim:

The ornamental design for a camper trailer, substantially as shown and described.
